UNITED STATES PATENT OFFICE.

ANDREW E. BAKER, OF NAPA, CALIFORNIA.

ANTISLIPPING DEVICE FOR SHOES.

1,008,773.

Specification of Letters Patent. Patented Nov. 14, 1911.

Application filed March 14, 1911. Serial No. 614,296.

To all whom it may concern:

Be it known that I, ANDREW E. BAKER, a citizen of the United States, residing at Napa city, in the county of Napa and State 5 of California, have invented new and useful Improvements in Antislipping Devices for Shoes, of which the following is a specification.

The invention relates to anti-slipping devices for shoes, and more particularly to the class of sole and heel calk attachments.

The primary object of the invention is the provision of an anti-slipping device of this character which is especially adapted for 15 use on the shoes of woodsmen in the lumbering camps and also baggers and on the river drives so as to give positive footing to such persons while at work.

Another object of the invention is the provision of an anti-slipping device which may be readily mounted upon and detached from 20 footwear, and when the device is in use will prevent the pedestrian from slipping while walking over ice or climbing hill sides, thus assuring a positive tread when walking upon 25 slippery surfaces with the same assurance as upon the street or pavement under ordinary conditions.

A further object of the invention is the 30 provision of a device of this character which may be adjusted to varying sized footwear, whereby the same may be securely clamped thereon for use in walking upon slippery surfaces, thus avoiding the slipping of the 35 pedestrian as would ordinarily occur should the device be not present upon the footwear.

A further object of the invention is the 40 provision of a device of this character which is simple of construction, strong, readily and easily applied to and detached from footwear, and that may be manufactured at a minimum expense.

With these and other objects in view, the invention consists in the construction, combination and arrangement of parts, as will be hereinafter more fully described, illustrated in the accompanying drawings, and pointed out in the claims hereunto appended.

50 In the drawings: Figure 1 is a bottom plan view of a shoe, showing the anti-slipping device applied both to the heel and sole thereof. Fig. 2 is a side elevation. Fig. 3 is a perspective view of the anti-slipping device for the heel of a shoe, the same being shown removed therefrom. Fig. 4 is a per-

spective view of the anti-slipping device for the sole of the shoe, the same being removed therefrom. Fig. 5 is a sectional view on the line 5—5 of Fig. 1.

60

Similar reference characters indicate corresponding parts throughout the several drawings.

Referring to the drawings by numerals, 2 designates generally a shoe having a sole 3 and a heel 4, the same being of the ordinary well-known construction, and to which are attached the sole and heel anti-slipping devices, as will be hereinafter more fully described.

65

The sole anti-slipping device comprises a pair of sections 5 and 6, each being formed from a single piece of sheet metal cut out, as at 7, to lighten the weight thereof, the sections being connected at the toe by means of a pivot 8, whereby they may be adjusted toward and away from each other. At the opposite ends of these sections 5 and 6 are formed outer cylindrical-shaped sleeves 9, while the section 5 is further provided at its inner end with an intermediate cylindrical shaped sleeve 10, the same alining with the sleeves 9 and through which is passed, an adjusting bolt member 11 provided at one end with a squared head 12 to be engaged by a suitable key for the turning thereof, while its opposite end is provided with threads 13 adapted for adjustable engagement with internal threads 14 formed in the sleeve 9 on the section 6. Thus it will be 75 seen that on the turning of the bolt member 11, the sections 5 and 6 may be adjusted toward and away from each other, as the occasion may require.

70

Struck up from the outside edges of the 80 sections 5 and 6 at intervals are gripping ears or clips 15, the same being provided with inturned free extremities 16, the clips 15 being adapted to engage with the peripheral edge of the sole 6 of the shoe, and their 85 inturned free extremities 16 will overhang the upper surface of the sole, so that when the bolt member 11 is turned in one direction the sections will be securely clamped to the sole.

90

Formed in the inner edge of the section 5 are notches 17, in which are engaged lugs 18 mounted in the section 6 which serve as stops for limiting the inward swinging movement of the sections toward each other.

100

Riveted or otherwise secured to the outer 110 faces of the sections 5 and 6 are reinforce-

ing strips 18', in which are suitably fastened pointed calks 19, the same being arranged in spaced relation to each other and are adapted to penetrate the ground, ice, snow or sleet 5 during the walking of a pedestrian thereover, thus preventing the slipping of the foot when treading upon the slippery surface. The anti-slipping heel device comprises a pair of sections 20 and 21, each being formed from sheet metal material, bent 10 into arcuate shape, the sections at adjacent ends thereof being connected by means of a pivot 22, while their opposite ends are bent to form alining sleeves 23 and 24, respectively, the sleeve 24 being provided with internal threads 25 engaged by the threaded end 26 of an adjusting bolt 27, the latter being loosely passed through the sleeve 23, so that on adjustment of the said bolt 27, 15 the sections may be moved toward or away 20 from each other.

Formed at the outside edges of the sections 20 and 21 are upturned gripping ears or clips 28, having inturned free ends 29, 25 the same being adapted to engage with the heel 7 of the shoe for the mounting of the sections thereon on adjustment of the bolt 27 for moving the sections 20 and 21 together or toward each other. Riveted or otherwise 30 secured to the outer faces of the sections 20 and 21 are reinforcing strips 30, in which are fastened pointed calks 31, the latter being arranged in spaced relation to each other and are adapted to penetrate the ground, 35 ice, sleet or snow, in an identical manner as the calks on the anti-slipping sole device.

Secured to the clips 28 is a continuous wire 32, the extremities thereof being suitably made fast to the sleeves 23 and 24, and 40 this wire is designed to prevent the outward spreading of the clips on the securing of the anti-slipping device to the heel of the shoe.

At a point spaced from the pivot 22 connecting the sections 20 and 21, and provided in the section 20 is a notch 33, in which is engaged a lug 34 mounted in the section 21, the said lug being adapted to limit the inward swinging movement of the section 21 45 toward the section 20 on the adjustment of the bolt carried thereby.

The lugs 18 and 34 are provided with heads 35, which prevent the outward separation of the sections of the device at right

angles to the axis of the pivot connecting the 55 same when these lugs are engaged in the notches adapted to receive the same.

From the foregoing description, taken in connection with the accompanying drawings, it is thought that the construction and 60 operation of the invention will be readily understood, without requiring a more extended explanation, and therefore the same has been omitted.

What is claimed is:

1. An anti-slipping device, comprising a 65 pair of sections pivotally connected together to permit the swinging of the same toward and away from each other, sleeves formed at the free ends of the sections, one of said sleeves being internally threaded, a bolt member adjustably engaged in the threaded sleeve and loosely passed through the remaining sleeve, a squared head formed on said bolt member and adapted for engagement with a key, clips formed at the outside edges of the said sections, calks connected with the sections and projecting therefrom, one of said sections being provided with a notch at its inner edge, and a headed lug carried by the other section 70 and adapted to engage in the notch.

2. An anti-slipping device, comprising a 75 pair of sections pivotally connected together to permit the swinging of the same toward and away from each other, sleeves formed at the free ends of the sections, one of said sleeves being internally threaded, a bolt member adjustably engaged in the threaded sleeve and loosely passed through the remaining sleeve, a squared head formed on said bolt member and adapted for engagement with a key, clips formed at the outside edges of the said sections, calks connected with the sections and projecting therefrom, 80 one of said sections being provided with a notch at its inner edge, a headed lug carried by the other section and adapted to engage in the notch, and means on the sections 85 for reinforcing the same and the points of connection of the calks therewith.

In testimony whereof I affix my signature in presence of two witnesses.

ANDREW E. BAKER.
